UNITED STATES PATENT OFFICE.

HARMON O. NELSON, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

ROVING-FRAME.

1,116,469.

Specification of Letters Patent.

Patented Nov. 10, 1914.

Application filed December 19, 1911. Serial No. 666,732.

To all whom it may concern:

Be it known that I, HARMON O. NELSON, a citizen of the United States, residing in Whitinsville, county of Worcester, and 5 State of Massachusetts, have invented certain new and useful Improvements in Roving-Frames.

The invention has particular reference to the means for protecting and closing in the 10 driving mechanism of roving frames, and its object has been to secure the inclosing casing in place without the addition of complicated or protruding parts, and in such manner that the upward contact of the spindle gears therewith cannot dislodge the casing, and so that such spindle movement will 15 be positively limited by such contact, and the general efficiency of the machine correspondingly improved, all as will be apparent 20 to those skilled in this art from the description given below and the drawings forming part hereof.

Referring to the drawings, Figure 1 shows in perspective view a section of the spindle 25 driving mechanism of a roving frame with the casing held in place by the means constituting the present invention; Fig. 2 is a vertical transverse section through the same frame and casing showing also the bobbin 30 carriage mechanism and one of the bobbins in longitudinal section; Fig. 3 is a detail of the preferred form of holding device; and Figs. 4 and 5 are modifications of such preferred form.

The spindle driving mechanism is mounted on a fixed rail 1, which is suitably supported on the frame of the roving machine in the usual or approved manner. At intervals along its length, the rail is equipped 40 with a series of bracket arms 2, which form the journal bearings for the spindle driving shafts 3 as well as the footstep bearings 4 for the spindles 5. There are brackets, such as 2, on both sides of the rail as shown in the 45 drawing, so that there are thus two driving shafts, 3, and two rows of footstep bearings with spindles 5 mounted in each. Each spindle is provided near its foot with a spindle gear 6, meshing with one of the corresponding bevel gears 7 on one of the shafts 3, through which driving connections the spindles receive their rotary motion. The spindles find their upper bearings in the bobbin carriage mechanism, the particular con-

struction of which does not of itself form a 55 part of this invention. In the present case, such mechanism comprises the bolster rail 8 carried on a part 9, that is connected to other parts not shown, whereby the bobbin carriage as a whole receives a vertical traverse 60 motion as required for the proper building of the yarn upon the bobbin. The bolster rail carries the bolster tubes 10, which surround and form the upper bearings for the spindles 5 as well as for the bobbin gears 11 65 upon which the bobbins 12 are placed and by which they are rotated. The upper end of the spindle protrudes above the bolster tube 10 and bobbin, at which point it is tapered and slotted to receive the flier 13, the hub of 70 the flier being internally tapered and keyed to match and fit non-rotatably upon the tapered end of the spindle. The bolster rail also forms the support for the shafts 14 and the skew gears 15 by which the bobbin gears 75 are driven, and also carries a gear casing which protects and covers these rotating parts. This gear casing is shown as of a usual design but, as will later appear, it may be secured in place in the same way as the 80 lower casing which illustrates this invention. The lower casing protects the spindle driving gearing and also forms an abutment to limit the upward movement of the spindle and assist in the removal of the fliers therefrom. Such upward movement of the spindles normally occurs from the effort to 85 remove the fliers therefrom when preparing to doff the frame. The fliers frequently stick to the spindles and the attempt to lift them off pulls the spindles upwardly out of their footstep bearings, causing the spindle gears to strike the gear casing, and the latter, if not specially secured in position or exceedingly massive in its design, becomes thereby 90 knocked out of position, so that it is frequently necessary for the operative to take both hands to separate the flier from the spindle without disarranging the parts of the frame. The features of this invention 95 allow the casing to be readily separable or movable on its support when necessary without rendering it insecure against such causes of displacement and at the same time constitutes the casing as an abutment for the 100 spindle gear to strike upon, of such substantial quality that by striking it the flier is thereby released. Such casing is also suffi-

ciently remote from the spindle gears as to be free from the risk of striking fire by contact therewith when under certain abnormal conditions the spindle gear is rotating above its proper position.

The improved casing is preferably divided transversely into sections, each of which is conveniently of a length which will accommodate about six of the spindles, as shown in Fig. 1, and the adjacent approximate ends of the successive sections are movably or separately mounted on common supporting frames. These frames, marked 16, are secured to the fixed rail 1 between the shafts 3, being conveniently formed of about the shape as shown in the drawings, the T-shaped heads of the frame being provided with downwardly and slightly outwardly sloped arms 16^a. Each section of the casing is divided lengthwise into a roof and two side-wall members, and the lines of division between these members are made to coincide with the lines of centers of the two rows of spindles so that the openings in the casing which accommodate the spindles are thus formed in the edges of the members. The top or roof member 17 is placed between the rows of spindles and rests by gravity upon the flat T-head of the frames. This member may be a wooden board, so that it can be conveniently lifted and withdrawn endwise through the space between spindles. The two side wall members 18 are placed upon or against the arms 16^a of the frames, and each is composed of an upright portion 18^a which closes in the side of the driving gearing, and an upper portion 18^b which is turned over to meet the member 17 in a substantially horizontal position, in which this upper portion overhangs the row of spindle gears 6 so that it will be encountered thereby when the spindle is lifted out of its foot-step bearing. The side wall members of the casing, on opposite sides of the frame, may be duplicates of each other; and each rests by its ends on the supporting frames where it is held in place by means of two independent holding devices. One of these devices consists, in its preferred form of an upstanding lug or horn 19 placed near the end of the T-head of the frame, and adapted to engage in a slot 20 cut in the end of the side-wall member. When so engaged the lug or horn prevents lateral movement of the upper part of the member. The other holding device consists, in its preferred form, of a laterally disposed lug 21 placed lower down on the supporting frame near the end of the arm 16^a. This lug is adapted to engage with an end slot 22 cut in the lower part of the upright portion 18^a and is intended to prevent upward movement of such portion, for which purpose the under surface of this lug is preferably sloped inwardly and upwardly as shown in Fig. 3. The last men-

tioned holding device, while preventing upward movement of the casing member, as just stated, allows the lower edge thereof to be grasped and swung outwardly and out of its engagement with the lug 21, whereupon the overhanging portion 18^b may then be lifted off the upstanding lug 19. The casing member can thus be removed. When replaced the overhanging portion is first placed over the upstanding lugs and the side wall portion is then dropped over the lateral lugs, to which position it moves by gravity, it being quite impossible to engage the lugs with their slots in the reverse sequence, or to disengage them except by first swinging the lower edges outwardly. When in place on the supporting frame the entire series of casing supports is covered and concealed from view, presenting an outer casing surface which is smooth and easily wiped. Impingement by the spindle gears upon the underside of the part 18^b of any casing member is unavailing to lift the member from the frame or displace it for the said member fulcrums against the upstanding lugs and the lower edge thereof is thereby pressed farther in the direction to engage it with the lateral lugs 21, which the more securely lock it in place. Instead of the laterally projecting lugs the same holding effect can be obtained by using the recesses 23 of the frame arms 16^a, such as shown at the left hand side of Fig. 4, or the lower end surface 24 of the arms, as shown at the right of the same figure, with either of which the casing can engage by means of its inturned lip 25. In both cases it will be observed that it is the downwardly exposed bearing surface which forms the holding device to prevent upward movement but permitting outward movement, and it will be also observed that this laterally disposed holding surface, as well as the upstanding bearing surface provided by the lug 19, may be made of any desired shape, extent or contour. Both bearing surfaces preferably extend full across the width of their frame so as to accommodate both ends of two adjoining casing members, and also each of these bearing surfaces is preferably formed by projecting lugs on the frames as in the case shown in the drawings, in which case the lugs are cast as integral parts of the frames, it being thus evident that no special or additional parts are necessary for attaining the benefits above described.

While the side wall members of the casing are desirably formed of metal, and can be made of very thin sheet metal, it is evident they can be made of any other suitable material, and that various other changes and modifications in the form, proportion and construction of the parts can be resorted to without departing from the principle of the invention.

Claims:

1. In a roving frame having a spindle and spindle gear, means for protecting the latter comprising a suitable support provided with a projecting holding device, in combination with a movable casing side-wall overhanging the spindle gear and adapted to be applied and removed over said holding device, being held against upward movement thereby, whereby upward movement of the spindle is limited by the engagement of its gear with the overhanging part of the side-wall and dislodgment of the latter is prevented.
- 15 2. In a roving frame, protecting means for the driving gearing thereof, comprising several fixed supports and a removable casing transversely divided into sections supported by their proximate ends on the supports, the said casing sections comprising roof and side members, and the side members being provided with end formations adapting them to interlock with the supports against separation therefrom by the 25 upward vertical movement of the gearing inclosed thereby.
3. In a roving frame, a spindle and spindle-gear and protecting means for the latter comprising an upright side-wall member provided with an upper portion turned inward to overhang the spindle-gear, in combination with a supporting frame for the said wall member provided with two independent holding devices for holding the 35 same in position thereon, one of said devices being adapted to prevent lateral movement of the said overhanging portion, and the other to prevent upward movement of the upright portion, the wall members being 40 removable by first laterally moving the upright portion from its holding device.
4. In a roving frame, a spindle and spindle gear and protecting means for the latter comprising a support and a side wall closure 45 thereon having a part overhanging the gear, and having separated points of attachment to the support, one of said points constituting a fulcrum bearing for the side wall closure under the upward action of the spindle gear thereon, and causing it to bind on the other point of attachment.
- 50 5. In a roving frame, the combination

with the vertically movable spindle-gear, a support, a casing movably mounted thereon comprising side-wall members having horizontal portions overhanging the gear, an upright bearing surface on the support engaging and laterally supporting the said overhanging portion, and a laterally disposed bearing surface on the support engaging the 55 upright portion of the side wall.

6. A gear protecting means for roving frames comprising a series of supports provided with upstanding lugs and removable casing sections slotted to receive the lugs in 65 combination with means for securing the casings in position on the lugs consisting of downwardly exposed bearing surfaces on the supports engaging corresponding abutment surfaces on the casings.

7. A gear protecting means comprising a series of supports with T-heads and depending arms at the ends of the head, and casing members mounted on the arms with upper portions overlying the T-head, in combination with a holding device for said overlying portion consisting of an upright bearing surface on the support engaging a corresponding surface on the casing member and a holding device on the arm consisting of a 75 laterally extending downwardly facing surface engaged by another surface on the casing member.

8. A roving frame comprising a vertically movable spindle and spindle gear, a freely 85 removable casing member inclosing and overhanging the gear, and means for rendering said casing immovable to the upward action of the spindle gear thereon.

9. A roving frame comprising vertically 90 movable spindles and spindle gears, a plurality of casing supports, a casing thereon composed of separate freely removable casing members placed upon and concealing the supports and means for rendering said members immovable by the upward action of the 95 spindle gears thereon.

In testimony whereof, I have signed this specification in the presence of two witnesses.

HARMON O. NELSON.
